Patented Feb. 20, 1917.

UNITED STATES PATENT OFFICE.

WILLIAM E. SMITH, OF MILLTOWN, NEW JERSEY, ASSIGNOR TO KILBOURN MANUFACTURING CORPORATION, OF NEW BRUNSWICK, NEW JERSEY, A CORPORATION OF NEW JERSEY.

SEAMLESS-FASHIONED STOCKING AND PROCESS OF KNITTING AND FASHIONING THE SAME.

1,216,374.

Specification of Letters Patent. Patented Feb. 20, 1917.

Application filed March 9, 1914. Serial No. 823,361.

To all whom it may concern:

Be it known that I, WILLIAM E. SMITH, a citizen of the United States, residing at Milltown, in the county of Middlesex and State of New Jersey, have invented certain new and useful Improvements in Seamless-Fashioned Stockings and Processes of Knitting and Fashioning the Same; and I do hereby declare the following to be a full, clear, and exact description of the invention, such as will enable others skilled in the art to which it appertains to make and use the same.

My invention consists in the novel features hereinafter described, reference being had to the accompanying drawing which illustrates diagrammatically one embodiment of my invention selected by me for purposes of illustration, and said invention is fully disclosed in the following description and claims.

In the accompanying drawing, the figure represents diagrammatically a fashioned seamless half hose embodying my invention.

In the knitting of seamless hosiery, the fabric is formed upon a circular series of needles, and the fabric produced by ordinary or plain knitting of the needles of the circular series, necessarily results in a tube which is not adapted to fit the human foot. In order to produce a seamless stocking which shall approximately have the form of the human foot, it has been customary to knit as excrescences on the tubular fabric the heel and toe pockets by stopping a portion of the needles, to wit, those which knit the front portion of the stocking, and knitting by reciprocating work and narrowing and widening to produce these heel and toe pockets at opposite ends of the foot portion, the leg and foot portions of the stocking being of tubular form. Owing to the character of the machinery employed in the knitting of seamless stockings, great restrictions are placed upon any variations from tubular fabric and for many years this class of stocking has been formed with the tubular leg and foot portions and the narrowed and widened toe pockets, as above indicated. When stockings are so made they do not accurately fit the foot, but are ironed upon boards so as to give them what might be termed "selling shape" which stretches the

stocking into a shape more nearly approximating that of the human foot. This boarding or shaping of the stocking, however, is purely artificial and has no relation to the structure of the fabric and it is therefore immediately lost when the stocking is laundered.

At the present time the demands of the trade require that the leg and top portion of the foot of the stocking shall be a fine closely knit fabric and the trade is demanding constantly a finer and finer web in the leg and top of the foot. In order to make the wearing qualities of the stocking satisfactory, it has been customary to reinforce the heel and toe and bottom of the foot with an additional thread, or to knit such portions of a heavier thread, and the effect of such reinforcing as ordinarily performed, tends to shorten as well as thicken the portions so reinforced and make them less elastic than the non-reinforced portion on top of the foot and at the leg, and when such stockings are laundered the heavier or reinforced portions tend to contract and become less elastic and shorter. It therefore follows that in most seamless stockings sufficient room is not afforded along the bottom of the foot and as the top portion of the foot is more elastic, there results a draw around the heel and toe of the stocking, which tends to drag down the high spliced portion above the heel and to draw the toe joining on the top of the foot where the toe pocket is looped or joined to the edge of the top of the foot forward over the toes, and the result is that if the wearer selects a stocking which is sufficiently long at the bottom of the foot for comfort, the top of the foot and the ankle portion of the stocking is too loose and sags and wrinkles while, if a stocking is selected which is small enough and fits snugly at the top of the foot and around the ankle, it is entirely too short around the bottom. These objectionable features are exaggerated when the stockings are laundered.

It is a fact that in order to make a seamless stocking to fit the foot of the wearer properly, it should be sufficiently longer along the bottom of the foot than over the top of the foot to make the bottom portion of the foot from a half size to a size longer.

than the corresponding top portion of the foot of the stocking, so that when the stocking is distended on the foot, the bottom portion, which is usually reinforced and is less elastic than the top of the foot, will extend preferably a little beyond the union between the toe pocket and the top portion of the foot so as to relieve the sole portion of the foot from longitudinal strain and permit the top portion of the foot to be smoothly and evenly stretched over the instep and top of the foot without undue spreading of the wales. My present invention consists in fashioning the stocking in the process of knitting the same so as to effect this result which enters into the permanent structure of the stocking and is not affected by subsequent laundrying of the same, and my invention covers the new stocking structure so produced.

In carrying out my invention, reference being had to the figure of drawing, which shows a half hose or men's stocking embodying my invention, 1 represents the ordinary top portion of the stocking which may be the usual ribbed top, and 2 represents the leg portion of the stocking, which is preferably knit with a fine thread by circular knitting down to the point indicated by the line $a-b-c$, where the heel pocket is to be formed. If desired, the rear portion of the leg above the heel may be knit as a heavier fabric either by means of a reinforcing thread or by knitting this portion of the leg with a heavier thread, to form what is termed the "high splice," indicated at 2'. When the circular course, indicated at $a-b-c$ is reached, the front needles will be thrown out of operation in the usual manner and the portion 3^a of the heel will be knit by reciprocating work and narrowing, until the narrowest course of reciprocating work, indicated by the line $f-e$ is reached. These courses I term the main narrowing courses as they are the normal narrowing courses of the heel. The narrowing will be effected in the usual manner by throwing out of operation, alternately, needles at opposite sides of the machine. The fabric is then widened by a series of reciprocating courses which I term the first part of the main widening courses less in number and preferably substantially half the number of the main narrowing courses, until the point indicated by the line $b-d-d'$ is reached, when the fabric is again narrowed and a series of additional narrowing courses substantially equal in number to the previously made main widened courses are knit by reciprocating work until the fabric is narrowed, as indicated at $g-h$, to the same extent as at the narrowing course indicated at $f-e$. The fabric is then widened until all of the needles of the rear half of the fabric have been brought into operation. This may be done

in several ways, but I prefer that in knitting the first widened course after the course $h-g$, to throw into operation simultaneously all of the needles from the point g to the point d at each side of the fabric so as to knit the first widened course from the point h' to the point d thus making it equal in length to the last preceding main widening course at $d'-d'$ and successive widened courses thereafter in the usual manner, by alternately bringing into operation one needle at each end of the reciprocating courses until the course $l-b$ is reached, when all of the needles previously thrown out of operation have been restored to operative position so that the course $l-b-c$ represents a continuous circular course. The widening courses between lines $h'-d$ and $l-b$ I term the second part of the main widening courses, as it will be seen that the first and second parts of the main widening courses constitute the same quantity of fabric as would be produced by the normal number of widening courses knit in the usual manner and that the additional narrowing courses comprised between lines $d'-d$ and $h-d$ constitute the inserted portion of fabric which has its main width at the bottom of the foot and forward of the exterior heel point e , so that it greatly lengthens the bottom of the foot of the stocking, making it in fact a size or more larger than the top of the stocking without materially increasing the size of the heel. In fact, this invention is to be clearly distinguished from prior inventions which sought to produce an enlarged heel pocket by making insertions above and below the heel pocket or at a number of points throughout the heel for the purpose of swelling out the heel of the stocking, as the object of my invention is not to increase the size of the heel, but to increase the length of the bottom of the foot, and make it a size longer than the corresponding top portion. The circular knitting is resumed so as to form the foot portion of the stocking, which comprises the top portion of the foot 4, and the bottom portion 5, the latter being preferably knit as a heavier fabric, either by use of a reinforcing thread or by knitting it with a heavier thread. The toe pocket 6 is then knit in the usual manner and the stocking is completed by joining the toe pocket to the forward edge of the top of the foot in the usual manner, forming the toe joining 7.

In knitting the heel of the stocking in the manner hereinbefore described, the heel pocket instead of comprising as heretofore, a narrowed portion and a widened portion, will comprise a narrowed portion 3^a, the small widened portion 3^b, another narrowed portion 3^c of substantially the same size as the widened portion 3^b, and the widened portion 3^d. The effect of this is to insert

into the bottom portion of the heel a segmental piece of fabric, indicated at g^c , and lying between the dotted line $d'-d$ and the line $h-d$, which effects a number of important structural changes in the shape of the stocking, and fashions the stocking to fit the foot. In the first place, this inserted segmental portion in the heel adds a considerable amount of length to the bottom portion of the stocking, to wit, the distance between the dotted line $d'-d$ and the line $d-h$, which also causes the foot of the stocking to set naturally more nearly at right angles to the leg portion of the stocking, which is the natural relation between the human foot and the leg, and it also removes the gather or pucker, which is present on each side of the heel of an ordinary seamless stocking at the opposite ends of the narrowest reciprocating course, and by providing a greater amount of fabric adjacent to the exterior portion of the heel, it prevents undue spreading of the wales upon the instep and facilitates the drawing of the ankle and instep portion of the stocking neatly and smoothly over the corresponding parts of the foot.

As a result of this structure, it will be seen that when the stocking is placed on the foot and distended by the foot, the bottom portion between the part of the heel indicated by line $d-d'$ (up to which line the knitting has proceeded in the same manner as in knitting the ordinary heel by narrowing and widening) and the toe pocket will contain a large number of additional courses beyond the number usually contained in those portions of seamless stockings, and as the standard size of a stocking is determined by the measurement from the exterior point of the heel to the point of the toe, a stocking of standard size, say size 10, can be made in this manner with less circular courses in the foot portion than would be required in the ordinary method of knitting a seamless stocking. As a matter of fact, I prefer to insert about thirty courses of reciprocating work between the point d' and the point h , and I may omit substantially the same number of circular courses from the foot portion of the stocking and still have the bottom portion of the stocking of the correct standard size, while the top portion will be considerably shorter than would otherwise be the case. The effect of this is to make the top part of the stocking from a half size to a size shorter than the bottom of the same stocking, or in other words, to produce, say a number 10 size stocking, having the bottom portion size 10, and the top portion of the foot corresponding to 9 $\frac{1}{2}$. This fashions the stocking effectively in the process of knitting, and when the stocking is worn, it is only necessary for the user to select a size which gives him a

proper length on the bottom of the foot, as the top portion of the foot being shorter, will be smoothly and evenly stretched and will lie neatly upon the foot without the formation of wrinkles. There will be no tendency to draw down the high splice at the rear of the stocking and no tendency to draw the toe joining forward over the toe joints and the stocking will be fashioned to the foot, and its shape will be permanent and not affected by subsequent laundering.

I do not limit myself to the exact details herein set forth as to the number of courses or the exact method of distributing the same, herein shown and described, as some variations may be made therein, without departing from my invention, the essential feature of which is the introduction at a point adjacent to the exterior point of the heel and the line of union between the heel pocket and the sole portion of the stocking, of a plurality of additional courses of reciprocating work for the purpose of elongating the bottom portion of the foot between the exterior point of the heel and the toe, and making the bottom portion of the foot substantially a size larger than the top of the same stocking to fashion the stocking to the foot.

Obviously my invention may be carried into effect by hand or by the use of certain forms of knitting machines, for example, it may be carried into effect by an ordinary circular knitting machine the needles of which are thrown out of and into operation during the reciprocating work may be raised and lowered by hand. My improved process may also be carried out by means of a knitting machine of the type shown, for example, in the United States patents to E. E. Kilbourn Nos. 408,180-1 of July 30, 1889, #432,946 of July 22, 1890, and #679,281 of July 23, 1901, in which mechanism is provided for automatically throwing the needles in and out of operation at the opposite ends of the reciprocating courses, by stopping the widening operation when the course d' to d has been reached in knitting the heel, and reversing the operation of the picker to cause the narrowing of the fabric to the point $d-h$, and then stopping the operation of the cam cylinder and throwing into operation the needles from g to d on both sides of the fabric, either by operating the picker mechanism without reciprocating the cam cylinder, or by otherwise replacing said needles in operative condition, and then continuing the widening operation until the point $l-b$ is reached, which variations in the operation of the machines described in said patents may be produced manually or by means of properly constructed pattern mechanism.

In the accompanying drawing, it will be understood that only one side of a stocking

or half hose is illustrated, and that in referring to the partial courses such as *a*—*b*, *f*—*e*, *d'*—*d*, *h*—*g*, *l*—*b*, etc., it will be understood that such courses extend from the points *a*, *f*, *d'*, *h*, and *l*, to corresponding positions on the other side of the stocking.

As my invention enables me to produce a stocking of any standard size with less courses in the foot portion than are required under the ordinary method of knitting, it is obvious that a saving in cost of manufacture is effected as a number of courses, say for example, thirty courses, are altogether omitted from the top of the foot 15 which is knit with more expensive yarn. This effects a very considerable saving in the manufacture of stockings in large quantities, and especially in the manufacture of lisle thread and silk stockings, in which 20 the leg and top of the foot are knit of the more expensive yarn, and the bottom of the foot and the heel and toe are formed of cotton.

What I claim and desire to secure by Letters Patent is:—

1. The herein described process of knitting and fashioning a seamless stocking which consists in the knitting of the heel by reciprocating knitting with a plurality of 30 main narrowing courses and a plurality of main widening courses, the widest courses of the heel being at the commencement of the narrowing courses and completion of the widening courses and extending approximately half way around the tube and knitting a plurality of additional consecutive inserted reciprocating courses of varying lengths at one point only between adjacent courses of the widened fabric formed by 40 said main widening courses to make the bottom portion of the foot substantially a size longer than the corresponding top portion to fashion the stocking to the foot.

2. The herein described process of knitting and fashioning a seamless stocking which consists in knitting the heel by reciprocating knitting with a plurality of main narrowing courses and a plurality of main widening courses, the widest courses 50 of the heel being at the commencement of the narrowing courses and completion of the widening courses, and extending approximately half way around the tube, and knitting a plurality of additional consecutive narrowing courses, at one point only, between two of said main widening courses, the widest of said additional courses being of less length than the widest main courses, and the narrowest of said additional courses 55 being of substantially the same length as the narrowest main narrowing course, to make the bottom portion of the foot of the stocking substantially a size longer than the top portion, to fashion the stocking to the foot.

3. The herein described process of knit-

ting and fashioning a seamless stocking, which consists in knitting the heel by reciprocating knitting with a plurality of main narrowing courses and a plurality of main widening courses, the widest courses of the heel being at the commencement of the narrowing courses and completion of the widening courses, and extending approximately halfway around the tube, and knitting a plurality of additional consecutive narrowing 70 courses at one point only between two of said main widening courses, the widest of said additional narrowing courses being of substantially the same length as the adjacent main widening course, and the narrowest of 80 said additional courses being of substantially the same length as the narrowest of said main narrowing courses, to make the bottom of the foot of the stocking substantially a size longer than the top portions of 85 the foot to fashion the stocking to the foot.

4. The herein described process of knitting and fashioning a seamless stocking, which consists in knitting the leg portion as a tubular fabric, knitting the heel by reciprocating work by first knitting a plurality 90 of main narrowing courses, the widest of which is approximately half of the length of the courses of the tubular fabric, then knitting a plurality of main widening 95 courses, then knitting a plurality of additional narrowing courses, and then knitting a plurality of widening courses to complete the heel, then knitting the foot as a tubular fabric and then knitting the toe pocket, 100 whereby a segmental additional portion of fabric is inserted in the portion of the heel adjacent to the sole of the stocking to make the bottom portion of the foot substantially a size longer than the corresponding top portion, 105 to fashion the stocking to the foot.

5. The herein described process of knitting and fashioning a seamless stocking, which consists in knitting the leg portion as 110 a tubular fabric, knitting the heel by reciprocating work, by first knitting a plurality of main narrowing courses, the widest of which is approximately half of the length of the last course of the leg, then knitting a 115 smaller number of widening courses, then knitting a plurality of additional narrowing courses, and then knitting a course of substantially the same length as the last previous main widening course and following it 120 with a plurality of main widening courses to complete the heel, then knitting the foot as a tubular fabric and then knitting the toe pocket, whereby a segmental additional portion of fabric is inserted in the heel adjacent 125 to the exterior point thereof to make the bottom of the foot substantially a size longer than the corresponding top portion of the foot to fashion the stocking to the foot.

6. The herein described process of knit-

- ting and fashioning a seamless stocking, which consists in knitting the leg portion as a tubular fabric, knitting a plurality of main narrowing courses, the widest of which is approximately half of the length of the last course of the leg, then knitting a smaller number of main widening courses, then knitting a plurality of additional narrowing courses, substantially equal in number to the preceding number of main widening courses, and then knitting a course of substantially the same length as the last previous main widening course and following it with a plurality of main widening courses to complete 70
- 15 the heel, then knitting the foot as a tubular fabric and then knitting the toe pocket, whereby a segmental additional portion of fabric is inserted in the heel forward of the exterior point thereof, to make the foot substantially a size longer than the corresponding top portion of the foot to fashion the stocking to the foot. 75
- 20 7. The herein described process of knitting and fashioning a seamless stocking which consists in knitting the leg portion as a tubular fabric, then throwing out of operation all the needles knitting the front portion of the leg, being approximately one half of the needles, and knitting the heel by reciprocating courses on the remaining needles, and first gradually narrowing said courses by throwing a needle out of action at each side of the heel, then knitting a plurality of courses and gradually widening by throwing 80
- 25 into action a needle at each side of the heel, then knitting a plurality of courses substantially equal in number to the number of preceding widened courses and narrowing by throwing a needle out of action at each side 85
- 30 of the heel, then throwing a plurality of needles simultaneously into operation at each side of the heel, and knitting a course of substantially the length of the last preceding widened course, and knitting a plurality of courses and widening the same by throwing a needle into action at each side of the heel, to complete the heel, then knitting the foot with all the needles as a tubular fabric, and finally knitting the toe pocket 90
- 35 by reciprocating knitting and narrowing and widening. 95
- 40 8. A fashioned seamless stocking having a plurality of additional courses of varying length inserted at one point only in that portion only of the heel between the normal heel suture and the last widening course of the heel corresponding with the first course of the heel, to make the bottom of the foot of the stocking substantially a size longer 100
- 45 than the top portion, and fashion the stocking to the foot. 105
- 50 9. A fashioned seamless stocking having a plurality of additional courses of varying lengths inserted at one point only in the portion of the heel adjacent to the sole of 110
- 55 the stocking, and between two normal widening courses thereof, to make the bottom of the foot of the stocking substantially a size longer than the top portion, and fashion the stocking to the foot. 115
- 60 10. A fashioned seamless stocking having a heel composed of a substantially equal number of gradually narrowed and widened courses and an additional number of gradually narrowed courses inserted at one point only between the point where the widened courses commence and the point where the heel unites with the foot of the stocking, to make the bottom of the foot of the stocking of greater length than the top and fashion 120
- 65 the stocking to the foot. 125
- 70 11. A fashioned seamless stocking having a heel composed of a number of gradually narrowed contiguous courses, a smaller number of contiguous gradually widened courses, adjacent thereto, a substantially equal number of contiguous gradually narrowed courses, and a number of gradually widened contiguous courses, the total number of widened courses being substantially 130
- 75 equal to the first mentioned number of gradually narrowed courses, whereby a segmental portion of fabric is inserted at one point only in the bottom of the heel forward of the point where the normal widening courses begin to make the bottom of the foot substantially a size longer than the top of the stocking and fashion the stocking to 135
- 80 the foot. 140
- 85 12. A fashioned seamless stocking, provided with a heel composed of a plurality of main narrowing courses, a smaller number of main widening courses, adjacent thereto, a plurality of additional narrowing courses adjacent to and forward of said 145
- 90 widening courses, the longest of said additional courses being substantially equal in length to the last of said widening courses, and the shortest of said additional courses being substantially equal in length to the 150
- 95 shortest main narrowing courses, and a plurality of main widening courses adjacent to and forward of the said additional courses, the shortest of said last mentioned widening courses being substantially equal 155
- 100 in length to the last previous widening course, and the longest being substantially equal in length to the first course of the heel, whereby the bottom of the foot of the stocking is made substantially a size longer 160
- 105 than the top to fashion the stocking to the foot. 165
- 110 13. Seamless hosiery having a heel pocket with Y-shaped side sutures of which the branches of the Y are considerably shorter than the stem of the Y. 170
- 115 14. The method of manufacturing seamless hosiery which consists in knitting the first part of the heel pocket by a narrowing operation upon the suture needles as usual; 175
- 120
- 125
- 130
- 135
- 140
- 145
- 150
- 155
- 160
- 165
- 170
- 175

then widening upon a limited number of the suture needles; then narrowing again upon the last mentioned suture needles; then widening upon all of the suture needles; the above mentioned limited number not exceeding one half of the total number of the suture.

In testimony whereof I affix my signature in the presence of two witnesses.

WILLIAM E. SMITH.
